UNITED STATES PATENT OFFICE.

OTIS B. COLCORD, OF GREENVILLE, ILLINOIS.

BUTTING ATTACHMENT FOR HARVESTERS.

SPECIFICATION forming part of Letters Patent No. 364,397, dated June 7, 1887.

Application filed May 5, 1886. Serial No. 201,205. (No model.)

To all whom it may concern:

Be it known that I, OTIS B. COLCORD, a citizen of the United States, residing at Greenville, in the county of Bond and State of Illinois, have 5 invented a new and useful Improvement in Butting Attachments for Harvesters, of which the following is a specification.

My invention relates to an improvement in butting attachments for harvesters; and it consists in the peculiar construction and combination of devices, that will be more fully set forth hereinafter, and particularly pointed out in the claims.

In the drawings, Figure 1 is a perspective view of a portion of a harvesting-machine provided with my improvements. Fig. 2 is a front end elevation of the same. Fig. 3 is a vertical longitudinal sectional view. Fig. 4 is an elevation of the reverse end from that shown in 20 Fig. 2.

The object of my invention is to provide an attachment for harvesting-machines to even the butts or cut ends of the straws in a sheaf before feeding the same to the binding-arms 25 on the binder-head.

A represents the elevator of a harvesting-machine, and B represents the binding-table, which projects from the rear upper end of the elevator and extends at about right angles 30 therefrom. This binding-table is provided with the slots C, through which the packing-arms pass to operate upon the sheaf. These arms and other portions of the operating mechanism of the harvesting-machine are not here 35 shown nor more particularly described, as they are of the usual construction, and form no part of my invention.

In the upper end of the elevator is journaled a transverse shaft, D, which carries the upper 40 end of the usual endless elevator-belt, E, the function of which is to carry the grain from the cutting apparatus to the binding-table. This shaft is rotated by means of a pulley, F, which is attached to one end of the shaft, and 45 is connected with a suitable operating-shaft of the harvesting-machine by means of an endless belt, G. The opposite end of the shaft D has a crank-arm, H.

I represents a butting-board, which is hinged 50 at one end to the rear upper side of the elevator. This butting-board is thereby adapted to vi-

brate over one side of the binding-table and to swing inwardly thereon toward the center of the binding-table. The upper and lower edges of the butting-board are provided with horizontal inwardly-projecting flanges K, which are made of sheet metal. From the outer side of the butting-board projects an arm, L, which is provided with a series of openings, l, at its outer end.

M represents a pitman, which is composed of two sections, m and m', which are hinged together. The front end of the section m' is attached to the crank H, in the usual manner, by means of a suitable wrist-pin, and the rear 65 end of the section m is attached to the arm L by means of a downwardly-projecting pin or bolt, m², which passes through one of the openings l.

From the foregoing description it will be 70 readily understood that the butting-board will be vibrated when the shaft D is rotated, and that the play or limit of movement of the butting-board may be regulated by adjusting the pin or bolt m² in the openings l.

To the upper end of the elevator, on the side opposite the butting-board, is hinged a board, N, which is arranged on the upper side of the binding-table on the side opposite the butting-board. This arm or board N is provided with 80 a spring, O, which bears against its outer side and keeps it normally moved inwardly over the binding-table in the position shown in Fig. 1.

The operation of my invention is as follows: When the machine is in motion, the grain is 85 elevated from the cutting apparatus by the carrier E and deposited upon the binding-table, where it is gathered by the packing-arms to form sheaves in the usual manner. Before each sheaf is compressed to form a gavel, the 90 butting-board I is moved inwardly over the binding-table by the rotation of the shaft D, and is thus caused to strike against the butts or cut ends of the straws, so as to force them lengthwise and arrange them on the same line, 95 thus squaring and evening the butt-end of the sheaf. As the straws are moved lengthwise across the binding-table in evening the butts of the sheaf, the headed ends of the straws are forced against the spring-pressed board N, 100 which yields sufficiently to the pressure of the sheaf to prevent the straws from being crushed.

and disarranged, but prevents them from being forced too far across the face of the binding-table by the operation of the vibrating butting-board. The function of the laterally-extending flanges K, with which the butting-board is provided, is to prevent the butt or cut ends of the straws from being forced apart when the butting-board strikes them.

A butting attachment thus constructed is exceedingly cheap and simple, is very easily operated, is not likely to get out of order, and is thoroughly efficient and practical in operation.

Having thus described my invention, I claim—

1. In a butting attachment for harvesters, the combination, with the elevator, of a binding-table whereon the grain is delivered, a vertical butt-board pivotally connected at one end to one side of the elevator and normally arranged flush with one edge of the binding-table, a horizontal arm rigidly affixed to the butt-board and extending outwardly therefrom, a crank-shaft actuated by the elevating means, and a two-part pitman connected at one end with the crank-shaft by a wrist-pin and adjustably connected at its opposite end with the fixed arm on the butter, to thereby vary the movement of the latter, the sections of the pitman being connected by a vertical pivot-bolt, as and for the purpose set forth.

2. In a butting attachment for harvesters, the combination, with an elevator, of a binding-table whereon the grain is delivered, a vibrating butt-board pivotally connected to one side of the elevator and normally arranged flush with one edge of the table, a yielding vertical board located at the other edge of the table and pivoted at one end to the elevator independently of the butt-board, a spring connected to the outer side of the elevator and the yielding board, to normally hold the latter in an oblique position with relation to the butt-board, a horizontal arm affixed to the vibrating butt-board, a shaft actuated by the elevating means and having a crank at one end, and a two-part pitman adjustably connected at one end to the horizontal arm of the butt-board by a pivot-bolt and at its opposite end to the crank on the shaft by a wrist-pin, the two parts of the pitman being connected by a vertical pivot-bolt, as and for the purpose described.

In testimony that I claim the foregoing as my own I have hereto affixed my signature in presence of two witnesses.

OTIS B. COLCORD.
